UNITED STATES PATENT OFFICE.

JOHN L. ARNOLD, OF CANTON, OHIO.

EXTENSION-TABLE LOCK.

No. 852,011.

Specification of Letters Patent.

Patented April 30, 1907.

Application filed October 18, 1906. Serial No. 339,443.

To all whom it may concern:

Be it known that I, JOHN L. ARNOLD, a citizen of the United States, residing at Canton, in the county of Stark and State of Ohio, have invented a new and useful Extension-Table Lock, of which the following is a specification.

The invention relates to a lock for a divided-pedestal extension-table having a center leg within the pedestal parts when closed, which center leg is usually made slightly shorter than the pedestal legs; and the object of the improvement is to provide a simple, economical and efficient lock which can be readily applied to any table of such general type, for engaging and drawing and holding together the pedestal parts when the table is closed.

This object is attained by the construction, mechanism and arrangement illustrated in the accompanying drawing, in which—

Figure 1 is a perspective view of the table showing the ends extended; Fig. 2, a fragmentary inside view of one pedestal part showing the lock applied thereto; Fig. 3, a vertical section of the pedestal parts locked together showing part of the top on the longitudinal middle line of the table, with the center leg broken away to disclose details of the lock; Fig. 4, a fragmentary view of the bail-finger joint; Fig. 5, a detached perspective view of one finger showing its pivot screw and the connecting part of the bail slightly separated therefrom; Fig. 6, a detached view of the crank shaft and supporting parts, showing the manner of adjusting the lock, and Fig. 7, a plan view of a fragment of the bridging with the crank shaft broken away, showing the laterally elongated eyes.

Similar numerals refer to similar parts throughout the drawings.

The table which is used to illustrate the lock comprises the top-halves 1 and 1^a with the end slides 2 attached thereto, the center leg 3 with the cross bar 4 and the neutral slides 2^a attached thereto, the intermediate slides 2^b having the ordinary tongue 5 and groove 6 connection with the end and neutral slides, and the pedestal parts 7 and 7^a with the pedestal legs 8 attached thereto, the same being attached to the top-halves on the under side of the end slides by means of the ordinary bridging or plates as 9.

The locking parts comprise the fingers 10, the bail 11, the operating crank 12, and the pins or posts as 13. The fingers are pivoted

preferably one on each inner side of the wall of one pedestal part 7, as by means of the headed screws 14, and the ends 15 of the fingers extend or protrude beyond the face of 60 the pedestal walls and are preferably curved downward to form somewhat of a hook. The ends 16 of the arms of the bail are pivoted to the other ends of the fingers, as by the rivet joint 17, as shown in Fig. 4; and the arms of 65 the bail preferably converge toward each other and extend upward through the notch 18 in the inner edge of the bridging, so that the apex or comparatively short cross bar 19 of the bail is located a short distance above 70 the bridging. The arms of the bail are preferably held in position and guided by the eyes 20, which may be elongated laterally of the table to accommodate the movements of the inclined arms of the bail, as shown at 20^a 75 in Fig. 7.

The crank shaft 21 is longitudinally journaled on the bridging of the pedestal part 7 as by means of the eyes 22 and 23; and may be held against endwise movement by the 80 crank shoulder 24 on one side and the kinked shoulder 25 on the other side of the eye-bearing 22. The outer end of the shaft is preferably bent at a right angle to form the handle 26, which is best adapted to normally 85 hang directly downward, as shown in Fig. 1; and in this relation, the crank proper 12 is preferably horizontally positioned and extends under and in contact with the head or cross-bar of the bail at one side thereof, as 90 shown in the same figure; which is the relation of the parts when the lock is open or disengaged and the pedestal parts are separated. An inwardly projecting post or pin 13 is located on each inner side of the walls 95 of the other pedestal part 7^a in such a position that when the lock is open the fingers will clear and pass over and beyond the posts when the pedestal parts are approximately closed together; whereupon the crank shaft 100 may be rotated and the bail raised by the crank operating upward and along the under side of the cross-bar to the opposite side thereof, as shown in Figs. 2 and 3, which 105 raising rotates the fingers on their pivots and forces their free ends downward and behind the posts on the opposite pedestal parts, and the pedestal parts are thus drawn together as shown in Fig. 3.

The parts are so proportioned and arranged that when the pedestal parts are drawn tightly together the crank has been

moved beyond the vertical or dead center to a point of rest against the opposite leg of the bail, as shown in Fig. 2, whereby the parts are automatically locked with the table parts tightly closed. To disengage the lock and separate the table parts, the crank shaft is merely rotated in the reverse direction, which leaves the bail free to drop or to be drawn downward, which movement is accomplished by the free ends of the fingers being lifted upward by the engaged posts as the pedestal parts are separated; whereupon the locking parts are in proper position for a re-engagement.

15 The necessary adjustment of the parts of the lock to fit it for its work in the first place, or to take up the wear and tear of the points of contact, or to compensate for a shrinking or an expansion of the wood parts of the table, is very readily and simply accomplished by raising or lowering the outer bearing-eye 23, which is easily done as by means of its threaded shank 27 extending through the bridging and the nuts 28 above and below 25 the same, which adjustment throws the operating crank downward or upward as may be necessary or desirable; and it will be noted that the arms of the bail can be flexed toward each other or spread apart to clear 30 the sides of the center leg and to fit and accommodate pedestal parts of various widths; and that the whole lock can be applied to any ordinary table of the type described without any important special preparation or 35 construction of the same.

By the use of the substantially inverted V-shaped bail, which may be slightly truncated as described, and by applying the power at the apex of the same, it is evident 40 that the arms of the bail are always in tension when the lock is operated and never perform their functions under a compression or a torsional strain; for which reason the power of the operating crank is communicated directly in a substantially straight line, and therefore positively, to each of the locking fingers, which is very important in a locking mechanism of this character wherein any lost motion or elasticity in the transmission 45 of the power is very objectionable and may be fatal to the proper and efficient operation of the lock.

What I claim as my invention, and desire to secure by Letters Patent, is—

55 1. A lock for a divided-pedestal extension-table comprising two posts on the inner sides of the walls of one pedestal part, a crank journaled on the bridging of the other pedestal part, two fingers pivoted on the inner sides of 60 the walls of the same pedestal part, and a bail with suitable guides having the ends of its arms pivoted to the inner ends of the fingers, and its cross-bar resting across the crank, the fingers being adapted to operate 65 against the upper-inner sides of the posts;

when the pedestal parts are proximately closed.

2. A lock for a divided-pedestal extension-table comprising two posts on the inner sides of the walls of one pedestal part, a crank journaled on the other pedestal part, two fingers pivoted on the inner sides of the walls of the same pedestal part, and a substantially inverted V-shaped bail pivoted to the fingers and adapted to be operated by the crank applied to its apex, the fingers being adapted to operate against the posts to close the table when the pedestal parts are brought approximately together.

3. A lock for a divided-pedestal extension-table comprising two posts on one pedestal part, a crank journaled on the other pedestal part, two fingers pivoted on the same pedestal part, and a substantially inverted V-shaped bail pivoted to the fingers and adapted to be operated by the crank applied to its apex, the fingers being adapted to operate against the posts to close the table when the pedestal parts are brought approximately together.

4. In a lock for a divided-pedestal extension-table, locking fingers pivoted on one pedestal part, an adjacent crank journaled on the same part, and a substantially inverted V-shaped bail pivoted to the fingers and having operative connection at its apex with the crank, means for vertically adjusting the operating end of the crank; and means on the other pedestal part adapted to co-operate with the fingers.

5. In a lock for a divided-pedestal extension table, locking fingers pivoted on one pedestal part, an adjacent crank journaled on the same part, and a substantially inverted V-shaped bail pivoted to the fingers and having operative connection at its apex with the crank; and means on the other pedestal part adapted to co-operate with the fingers.

6. In a lock for a divided-pedestal extension table, locking fingers pivoted on one pedestal part, an adjacent crank journaled on the same part, and an operative connection in a direct line between the crank and each of the fingers; and means on the other pedestal part adapted to co-operate with the fingers.

7. In a lock for a divided-pedestal extension table, locking fingers pivoted on one pedestal part, a flexible substantially inverted V-shaped bail connected with the fingers, and operating mechanism applied to the apex of the bail; and means on the other pedestal part adapted to co-operate with the fingers.

8. In a lock for a divided-pedestal extension table, locking fingers mounted on one pedestal part, a substantially inverted V-shaped bail connected with the fingers and having a cross bar at its apex, a crank mount-

ed on the same part adapted to operate against the inner side of the cross-bar and to be stopped against one side of the bail when rotated beyond the dead center; and means on the other pedestal part adapted to co-operate with the fingers.

5 In testimony whereof, I have hereunto

signed my name to this specification in the presence of two subscribing witnesses.
